UNITED STATES PATENT OFFICE

160,723

INTERIOR AUTOMOBILE DOOR TRIM PANEL

Joseph Landsman, Warren P. Landsman, and
Robert L. Landsman, Chicago, Ill.

Application July 10, 1948, Serial No. 147,494

Term of patent 14 years

(Cl. D14—6)

To all whom it may concern:

Be it known that we, Joseph Landsman, Warren P. Landsman, and Robert L. Landsman, citizens of the United States and residents of Chicago, in the county of Cook and State of Illinois, have invented a new, original, and ornamental Design for an Interior Automobile Door Trim Panel, of which the following is a specification, reference being had to the accompanying drawings, forming a part thereof.

The figure is a front elevational view of an interior automobile door trim panel, showing our new design.

The characteristic features of our design reside in the portions shown by full lines.

We claim:

The ornamental design for an interior automobile door trim panel, substantially as shown.

JOSEPH LANDSMAN.
WARREN P. LANDSMAN.
ROBERT L. LANDSMAN.
